UNITED STATES PATENT OFFICE

109,191

DESIGN FOR A PAJAMA ENSEMBLE

Helen Wolfe, Chicago, Ill., assignor to Maurice L. Rothschild, Incorporated, a corporation of Delaware

Application November 13, 1937, Serial No. 72,827

Term of patent 3½ years

To all whom it may concern:

Be it known that I, Helen Wolfe, a citizen of the United States, residing at 7706 East Lake Terrace, Chicago, Cook County, State of Illinois, have invented a new, original, and ornamental Design for a Pajama Ensemble, of which the following is a specification, reference being had to the accompanying drawing constituting a part thereof.

Fig. 1 is a front view of the pajama ensemble showing my design.

Fig. 2 is a rear view thereof.

Fig. 3 is a front view, without the jacket, of the pajama ensemble shown in Fig. 1.

Fig. 4 is a rear view of Fig. 3.

The instant ensemble comprises a three piece pajama suit consisting in the specific combination of full trousers, a shirtwaist collared blouse having a drop shoulder yoke in the front, a gathered yoke in the back, and short sleeves pleated in the front and back, together with a hip length jacket having the specific lapelled collar, full length, cuffed sleeves having peaked shoulders, and a sash belt, as shown.

I claim:

The ornamental design for a pajama ensemble, substantially as shown and described.

HELEN WOLFE.
